UNITED STATES PATENT OFFICE.

CHARLES K. HODGE, OF CONCORD, VERMONT.

MILK COOLER.

Application filed May 31, 1921. Serial No. 473,878.

To all whom it may concern:

Be it known that I, CHARLES K. HODGE, a citizen of the United States, residing at Concord, in the county of Essex and State of Vermont, have invented a new and useful Milk Cooler, of which the following is a specification.

This invention relates to liquid cooling devices, and more particularly to a device 10 employed for cooling milk or the like, to extract the animal heat therefrom.

The primary object of the invention is to provide a device of this character which will discharge the milk or fluid under treatment 15 over a cooling element in a fine film, thereby insuring the liquid contacting with the surface of the cooler.

A further object of the invention is to provide means for straining the liquid prior 20 to its passage to the cooling element, means being provided to retard the movement of the liquid over the cooling member.

With the foregoing and other objects in view which will appear as the description 25 proceeds, the invention resides in the combination and arrangement of parts and in the details of construction hereinafter described and claimed, it being understood that changes in the precise embodiment of the 30 invention herein disclosed, may be made within the scope of what is claimed, without departing from the spirit of the invention.

Referring to the drawings—

Figure 1 is a side elevational view of a 35 cooling device constructed in accordance with the present invention.

Figure 2 is a sectional view taken on line 2—2 of Figure 1.

Figure 3 is a vertical sectional view 40 through the cooling device.

Figure 4 is a sectional view taken on line 4—4 of Figure 1.

Figure 5 is a sectional detail view of the 45 cooling member, the figure illustrating a fragment thereof.

Figure 6 is a vertical sectional view taken through the supporting pipe and elements which support the straining member.

Referring to the drawings in detail, the 50 device includes a support having the legs 5 and upper circular member or supporting ring 6 which has connection with the legs 5 at the upper ends thereof. The body portion of the device comprises a circular member 7 and a tapered lower portion 8 which terminates in a downwardly extending cir-

cular flange 9, there being provided a flange 10 formed at the base of the member 7 for contracting with the ring 6 to support the body portion of the device within the ring 6. 60

The upper section of the body portion is circular in formation and indicated by the reference character 11, the same being provided with an extension 12 to be fitted in the member 7 as clearly shown by Figure 3 65 of the drawings. A bottom 13 is secured within the upper section 11 and is provided with a depressed portion 14 which is apertured to accommodate the pipe 15 which has openings 16 formed therein, the openings 70 being disposed above the lower wall of the depressed portion 14 to provide communication between the interior of the pipe 15 and interior of the upper section 11. Grooves 75 17 are formed in the pipe 15 and have their upper ends disposed adjacent to the openings 16 so that fluid passing through the openings 16 will be directed through the grooves 80 where the same discharges onto the cooling member to be hereinafter more fully described.

The straining member comprises a body portion 18 having its lower end disposed within the depressed portion 14 and having straining elements 19 supported thereby, the 85 straining elements lying in planes above the bottom 13 of the upper section 11 so that fluid passing from the upper section 11 will pass through the straining elements 19 before the same passes to the cooling member. 90

In order to further purify the liquid under treatment, a layer of cotton or similar filtering material indicated at 20 may be positioned within the depressed portion 14. Formed on the inner wall of the tapered 95 lower portion 8 are the spaced ribs 21 which contact with the wall of the cooling member 22 to support the same in spaced relation with the tapered lower portion 8, thereby providing passageways for the fluid 100 to pass from the device.

This cooling member 22 is hollow and is substantially inverted cone-shaped, to conform with the tapered lower portion 8, and as shown, the upper surface of the cooling 105 member 22 is inclined, as indicated at 23, the same being provided with spirally formed ribs 24 dividing the upper surface 23 into a plurality of curved passageways to cause the fluid passing thereover to take a 110 spiral course in its movement over the cooling member.

A delivering pipe indicated at 24' has one end thereof disposed within the cooling member 22, the opposite end thereof being positioned within the tank 25, which may be of any size capable of supplying liquid to the interior of the cooling member 22 for a sufficient period to accomplish the cooling of a quantity of fluid. A valve member 26 is positioned in the pipe 24' and controls the passage of cooling fluid from the tank 25 to the cooling member 22. A discharge pipe 27 also has one end thereof in communication with the cooling member 22 to permit the cooling fluid within the member 22 to circulate.

Positioned within the upper section 11 of the device is a supporting pipe 28 that is provided with grooves 29 adapted to register with the grooves 17 of the pipe 15 when the pipe 28 is rotated in one direction, but when the pipe is moved in a horizontal plane, the grooves 29 are moved out of registry with the grooves 17 to reduce the flow of fluid through the upper section 11, the rotary movement of the pipe being controlled by the pin 30 which is carried thereby and which moves in a relatively small cut out portion formed in the side wall of the pipe 15.

In the use of the device, a cooling fluid is positioned in the tank 25 the cooling fluid consisting of water iced to a predetermined degree. The fluid under treatment is poured into the upper section 11 of the device where the same filters through the filtering members 19 and 20 and passes through the openings 16 and onto the cooling member 22. The valve member 26 is now opened to permit the cooling fluid to pass into the cooling member 22. From the foregoing it will be seen that as the fluid under treatment passes through the passageways formed by the spirally disposed ribs 24, the low temperature of the member 22 cools the fluid passing thereover.

A can or other receptacle which in the present drawing is indicated by the reference character 31 is positioned under the discharge end of the device to receive the cooled fluid.

Having thus described the invention, what is claimed as new is:—

1. A fluid cooling apparatus comprising a body portion having an upper section and a lower section, a hollow cooling member disposed within the lower section, ribs carried by the lower section and contacting with the outer surface of the cooling member for supporting the cooling member in spaced relation therewith to provide a fluid passageway, spirally formed passageways on the upper surface of the cooling member, means for delivering fluid to the upper surface of the cooling member and to the passageways, means for filtering the fluid on its passage to the cooling member, and means for delivering a cooling fluid to the interior of the cooling member.

2. A fluid cooling apparatus comprising a body portion having an upper section and a lower section, a cooling member disposed within the lower section, a pipe for directing cooling fluid to the cooling member, a pipe surrounding the first mentioned pipe and having grooves formed in the outer surface thereof, means embracing the second mentioned pipe and having grooves registering with the second mentioned grooves to provide fluid passageways, and said fluid passageways adapted to deliver fluid to be cooled to the cooling member.

3. A fluid apparatus comprising a body portion including an upper section and a lower section, a cooling member disposed within the lower section, said upper section having an inclined bottom formed with a depressed portion, a pipe extending through the depressed portion, a filtering member embracing a portion of the pipe, said pipe having communicating openings and grooves, and said grooves forming passageways to allow material to pass to the cooling member.

In testimony that I claim the foregoing as my own, I have hereto affixed my signature in the presence of two witnesses.

CHARLES K. HODGE.
